United States Patent

Des. 235,756
Patented July 8, 1975

235,756

CYCLE STAND

Almon F. Townsend, % Persons-Majestic Mfg. Co.,
72 Commercial St., Worcester, Mass. 01608

Filed Sept. 10, 1974, Ser. No. 504,805

Term of patent 7 years

Int. Cl. D8—99

U.S. CL. D12—115

FIG. 1

FIG. 2

FIG. 3

FIG. 1 is a side elevational view of a cycle stand showing my new design, it being understood that the opposite side is a mirror image thereof;

FIG. 2 is an end elevational view thereof, the opposite end being a mirror image of the end shown herein; and

FIG. 3 is a top plan view thereof.

The broken lines shown in FIG. 1 of the drawing are for illustrative purposes only.

I claim.

The ornamental design for a cycle stand, as shown and described.
